CLAIM

The ornamental design for a portable grill, as shown and described.

DESCRIPTION

FIG. 1 is a front perspective view of the portable grill in an assembled configuration, with a grill surface a grate in position.

FIG. 2 is a side plan view of the assembled portable grill of FIG. 1.

FIG. 3 is a top plan view of the assembled portable grill of FIG. 1.

FIG. 4 is a rear plan view of the assembled portable grill of FIG. 1; and,

FIG. 5 is a bottom plan view of the assembled portable grill of FIG. 1.

The broken lines depict portions of the portable grill that form no part of the claimed design. The broken lines act as boundaries of the claimed design where they intersect claimed surfaces.
